DESIGN FOR A LAMP BRACKET

Herman E. De Vries, New York, N. Y., assignor
to H. T. Cushman Mfg. Co., North Benning-
ton, Vt.

Application February 7, 1935, Serial No. 55,293

Term of patent 3½ years

To all whom it may concern:

Be it known that I, Herman E. De Vries, a citizen of the United States, residing at New York city, in the county and State of New York, have invented a new, original, and ornamental Design for a Lamp Bracket, of which the following is a specification, reference being had to the accompanying drawing, forming a part thereof.

Figure 1 is a top plan of a lamp bracket showing my new design;

Figure 2 is a front elevation of the same; and
Figure 3 is a side elevation.

I claim:

The ornamental design for a lamp bracket substantially as shown.

HERMAN E. DE VRIES.
